CLAIM

The ornamental design for an evaporator bottle as shown and described.

DESCRIPTION

FIG. 1 is a perspective view of a first embodiment of an evaporator bottle according to the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof.

FIG. 8 is a perspective view of a second embodiment of an evaporator bottle according to the design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines depict portions of an evaporator bottle that form no part of the claimed design.

1 Claim, 14 Drawing Sheets
